UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed November 15, 1923. Serial No. 674,972.

The invention relates to draft gears for railway cars, being particularly adapted for use in freight service.

The principal object of the invention is 5 to secure a high efficiency by providing for the development of the maximum resistance of the gear at the inception of compressive action, and the maintenance of such maximum resistance until the gear is completely 10 closed.

The gear is furthermore so organized that certainty of release is secured. Further advantages of the gear will appear in connection with its description and manner of operation.

A preferred embodiment of the improved gear is illustrated in the accompanying drawings, in which

Fig. 1 is a central plan section of the gear 20 as applied to a car;

Fig. 2 is a sectional view of the gear on the line 2—2 of Fig. 1;

Fig. 3 is a plan section in part similar to Fig. 1 but mainly immediately above the friction elements, the gear being shown in full compression;

Figs. 4 and 5 are views in perspective of the wedging elements;

Fig. 6 is an elevation of one of a series of 30 friction plates of uniform shape;

Fig. 7 is a view similar to Fig. 1, showing the wedging and friction elements mainly in plan;

Fig. 8 is a central vertical section of the 35 gear showing a modified form of construction; and

Fig. 9 is a perspective view of one of the parts of the draft gear.

For the purpose of showing the manner of 40 mounting the gear in a car there is represented a pair of draft or center sills at 10, 10, a pair of draft lugs at 11, 11, a pair of buffing lugs at 12, 12, the butt of a coupler at 13, and a common form of yoke or coupler extension at 45 14. These elements form no part of the invention, and may be of any preferred form.

The gear is shown as comprising a plate follower 15, and a chambered follower 16, the former being associated with the draft lugs 50 and the latter with the buffing lugs, though their relative positions may be reversed without changing the action of the device. Within the chambered follower 16, and associated, respectively, with its two side walls, are two

groups of friction plates 17, 18, each group 55 being composed of two sets of intercalating plates of uniform shape, one of which is shown at 19 (Fig. 6).

The friction plates are shown as bifurcated or U-shaped, thus providing a transverse 60 horizontal chamber for the accommodation of releasing elements. The actual tying together of the upper and lower longitudinal members of the friction plates by means of an integral transverse portion, as shown, 65 while desirable, is not essential,—it being important that friction plates be provided above and below the releasing elements (any suitable means for preventing vertical displacement of the upper plates being used), 70 and that the plates have shoulders for engagement by a releasing element. The cross-member of the U-shaped plate forms a shoulder for this purpose.

The two sets of friction plates of each 75 group are normally so disposed that their united or shouldered ends, for convenience here called their rear ends, are in contact, or approximately in contact, with one of the followers, and the length of the plates is 80 such that their opposite or forward ends are spaced a sufficient distance from the other follower to permit the maximum compressive travel.

Within the chamber between the upper and 85 lower legs of the friction plates, and engaging the retracting shoulders of each, are a pair of bars 20, 21, extending from side wall to side wall of the chambered follower 16. The bar 20, which is adjacent the outer or 90 open end of this follower, is of such horizontal width that it at no time emerges entirely beyond the casing, thereby preventing its endwise displacement. The two bars 20, 21, comprise seats for a series of releasing 95 springs, as 22, shown as five in number.

Wedging elements, having their contacting faces sharply acute to the axis of the gear, are interposed between the two groups 17, 18, of the friction plates. One of these elements, as 23, is bifurcated in form to provide a continuance of the chamber within which the releasing elements are housed. The closed end of this wedging element is normally seated against the plate follower 15, 105 and bears forwardly upon the adjacent releasing bar 20. Each leg of the element 23 is provided with a plurality of wedging faces,

as 24, 25, the base 26 of the inner wedge 25 being formed as a shoulder and constituting a spring seat.

Cooperating with the wedging surfaces of each leg of the element 23 is a floating wedging element 27, having wedging faces 28, 29, complementary to and engageable with the wedging faces 24, 25; the base, 30, of the wedge 28 taking the form of a shoulder to provide a spring seat opposed to the seat 26. The wedging portions of both of the elements 23, 27, are united at one margin by horizontal webs 31, 32, the webs of the two elements being relatively so disposed that they constitute, respectively, the upper and lower wall of a spring chamber.

Housed within the chambers thus formed, and reacting between the seats 26, 30, are a pair of friction developing springs 33, 34. 20 In assembling the gear the springs 33, 34, are introduced under compression, and their reaction forces the cooperating wedging faces into engagement and consequently maintains a corresponding degree of lateral pressure 25 upon the two groups of friction plates.

The wedging elements 27 are at all times out of contact with the cross member of the chambered follower. The inner plate of each group, in contact with the wedges, is of the 30 set which cooperates directly with the chambered follower. The long taper of the wedging faces produces a very powerful wedging action, of which there is an immediate maximum development at the commencement of 35 the compression of the gear.

Under the influence of buffing stresses, with the gear and its parts normally positioned as shown in Figs. 1 and 7, the follower 15 moves backwardly, carrying with it the wedging 40 element 23 and the releasing bar 20. The advance of the wedging elements 27 being resisted by their frictional engagement with the adjacent friction plate, a maximum development of wedging action upon the friction 45 plates immediately occurs. The follower 15 now comes into engagement with the set of friction plates located adjacent to it and forces them forwardly between the members of the other set of plates, their advance being 50 resisted by the high friction due to the action of the wedges, the resistance continuing uniform throughout the entire compressive movement, which is arrested when the follower 15 comes into engagement with the 55 ends of the walls of the follower 16, as shown in Fig. 3.

The inward movement of the follower 15 and with it of the bar 20, has caused a compression of the releasing springs 22. When 60 the buffing stresses are removed the releasing springs force backwardly the bar 20, and with it the wedging element 23. As the elements 27 lag by reason of their frictional engagement with a stationary plate, the compressive 65 action on the two groups of plates is relieved.

The bar 20 presently engaging the shoulders of the two sets of friction plates which had been advanced, carries these plates back to normal position. The wedging elements 27 follow up the element 23 under the influence 70 of the springs 33, 34. The release, while prompt and certain, is without violence because some degree of wedging pressure is constantly exerted upon the two groups of friction plates. 75

Under the influence of draft stresses like results are secured, the wedge elements 27 being carried forward by the frictional engagement therewith of the adjacent plate which, as stated, is associated with and acted directly upon by the follower 16. 80

While a highly efficient and, so far as now advised, a preferred form of construction is shown and described, various changes of detail may be made within the scope of the invention. For example, in place of the springs 33, 34, for holding the wedging elements normally in wedging engagement, a spring may be employed which will react against one of the followers, as in the modification of Figs. 90 8 and 9. In this modification there is substituted for the pair of wedging elements 27 a single bifurcated element 35, the cross-member 36 of which constitutes a seat for a spring 37, which reacts against the bar 21, the central releasing spring of the set 22 being omitted. 95

The action of the gear in its modified form is the same as in the form previously described, with the exception that the spring 37 100 acts upon the wedging element 35 to oppose or cause its longitudinal movement as the gear is compressed as means for augmenting the wedging action. This spring is, however, preferably quite light, and the action 105 last referred to is negligible.

I claim as my invention—

1. A wedging member for use in a draft gear, comprising a body member provided with a plurality of inclined wedging portions, a shoulder between said wedging portions, said shoulder adapted to form an abutment for a spring, and a web connecting said wedging portions. 110

2. In a draft gear, a plurality of wedging members provided with a plurality of inclined wedging portions, the wedging portions of one member engaging the wedging portions of the other member, certain of said portions being opposed and provided with abutments, resilient means between said abutments tending to cause said members to move along said inclined surfaces, and flanges on said members for enclosing said resilient means. 115

3. In a draft gear, in combination, a chambered follower, a follower opposed thereto, two groups of intercalating friction plates enclosed within the chambered follower, each group comprising two sets of plates, the plates of each set of each group being end- 120 125 130

- wise engageable by one of the followers, co-operating wedging elements interposed between the two groups of plates, and in frictional contact therewith, resilient means between said elements, one of such elements being acted upon positively by one of the followers, the longitudinal positioning of the other wedging element being dependent mainly on its frictional engagement with one of the friction plates, and means for returning the parts to normal position after compression. 5
4. In a draft gear, in combination, a chambered follower, a follower opposed thereto, two groups of intercalating friction plates enclosed within the chambered follower, each group comprising two sets of plates, the plates of each set of each group being endwise engageable by one of the followers, co-operating wedging elements interposed between the two groups of plates and in frictional engagement therewith, one of such elements being acted upon positively by one of the followers, the longitudinal positioning of the other wedging element being dependent mainly on its frictional engagement with one of the friction plates, and spring means for normally urging the wedging elements together, and means for returning the parts to normal position after compression. 10
5. In a draft gear, in combination, a pair of opposed followers, two groups of intercalating friction plates interposed between the followers, each group comprising two sets of plates, the plates of the two sets of each group being endwise engageable, respectively, with each follower, means to limit the lateral movement of said plates, co-operating wedging elements interposed between the two groups of plates, means for holding the wedges in wedging relation to the plates, one of said elements being positively controlled by one of the followers and the other of such elements being controlled by the other follower mainly by frictional engagement with a plate engageable by such follower, and means for returning the parts to normal position after compression. 15
6. In a draft gear, in combination, a chambered follower, an opposed follower, two groups of intercalating friction plates interposed between the followers, each group comprising two sets of plates, one set of plates being adapted to be engaged by one of said followers, the two sets of plates of each group being relatively longitudinally movable by the relative approach of the followers, a pair of co-operating wedging elements interposed between the two groups of plates, and spring means positioned between said groups of plates and reacting between the two wedging elements for urging them together, and means for returning the parts to normal position after compression. 20
7. In a draft gear, a pair of co-operating elements each having a plurality of longitudinally arranged wedging portions in engagement with one another, the rear end of the advance wedging portion of each being formed as a shoulder, and an expansion spring reacting between such two shoulders. 25
8. In a draft gear, in combination, a pair of coupler engaging followers, two groups of longitudinally disposed intercalated friction plates interposed between the followers, means for limiting outward lateral movement of the plates, means interposed between the two groups of plates for exerting outward pressure thereon and arranged to develop maximum pressure at the initial compressive movement of the gear and to maintain such pressure to the end of such movement, a portion of such pressing means being in direct contact with one of the named followers when the gear is expanded. 30
9. In a draft gear, in combination, a pair of opposed coupler engaging followers, co-operating wedging elements having friction faces, one of said elements being in contact with one of the named followers during the initial compressive action of the gear, and elements having sliding engagement with such faces, said elements comprising intercalated friction plates, said wedges being arranged to maintain a substantially uniform pressure upon the second named element throughout their movement after the initial compressive movement of the gear. 35
10. In a draft gear, in combination, a pair of opposed coupler engaging followers, one thereof being a casing, two groups of intercalating friction plates enclosed within the casing, a pair of co-operating wedging elements interposed between and compressively acting upon the groups of plates, one of such elements being floating and the other being positively engageable by one of the named followers, spring means reacting between the wedging elements for urging them into engagement, each set of each group of plates being positively engageable by one of the said followers, the inner plate of each group being of the set which is not engageable by the follower engageable by the wedging element and other spring means for effecting the release of the gear. 40
